(57) **CLAIM**

The ornamental design for a vegetable stem stripping tool as shown and described.

DESCRIPTION

FIG. 1 is a perspective view of a vegetable stem stripping tool incorporating the design of the present invention;
FIG. 2 is a top view of the vegetable stem stripping tool of FIG. 1;
FIG. 3 is a bottom view of the vegetable stem stripping tool of FIG. 1;
FIG. 4 is a front view of the vegetable stem stripping tool of FIG. 1;
FIG. 5 is a rear view of the vegetable stem stripping tool of FIG. 1;
FIG. 6 is a left side view of the vegetable stem stripping tool of FIG. 1; and,
FIG. 7 is a right side view of the vegetable stem stripping tool of FIG. 1.
The broken lines show portions of the vegetable stem stripping tool that form no part of the claimed design.
